UNITED STATES PATENT OFFICE

2,127,242

HORSE-COLLAR PAD

Arthur Wesley, Chicago, Ill., assignor, by mesne assignments, to The American Pad and Textile Company, Greenfield, Ohio, a corporation of Ohio

Application February 2, 1938, Serial No. 188,253

1 Claim. (Cl. 54—67)

The present invention pertains to pads, such as are ordinarily used in the upper portions of horse-collars whereby to protect the corresponding portion of the animal from injury while wearing the collar during service.

One aim of this invention is to provide a horse-collar pad which permits a comparatively-free circulation of air through the pad, thus permitting sweat to be readily absorbed, transmitted to the outside of the pad, and there evaporated, whereby the animal's neck is maintained cool, comfortable, dry and clean, the cooling effect preventing scalding and gall-sores as well as aiding in healing sore necks.

A further purpose of the invention is to supply a pad of this type which is soft and pliable, which readily conforms to the shape of the collar and neck, which is soothing in effect, and which acts as an efficient shock-absorber.

An additional object of the invention is to make a horse-collar pad having the stated properties at small cost and which may be readily and easily applied to the collar and which effectively maintains its proper position therein during service.

To permit those acquainted with this art to fully understand the invention both from structural and functional standpoints, a present preferred embodiment of the invention has been illustrated in the accompanying drawing, in both figures of which like reference characters have been employed to designate the same parts.

In this drawing:—

Figure 1 shows the novel and improved pad applied to a horse-collar in position for use; and

Figure 2 is an enlarged perspective view of the pad supplied with its attachment straps.

By reference to this drawing, it will be readily perceived that the new pad or cushion 10 is rectangular in shape and of suitable thickness and it easily assumes a proper curved form when applied to the inside of the collar 11 as presented in Figure 1.

Obviously, such a pad should be flexible, pliable and elastic and to have the characteristics and properties mentioned above, I have found that sponge-rubber is especially adapted for such purpose, provided the surface rind produced thereon during its manufacture is stripped off or removed from both of its opposite faces, that is, from its top and bottom surfaces, whereby the pad is rendered porous throughout its entire thickness as can be easily demonstrated by blowing cigar or cigarette smoke through it.

The cushion or pad having been thus provided, it is necessary to equip or fit it with means for its attachment to the horse-collar, and, to this

end, the pad is slit crosswise at separated points at 12, 12, between its top and bottom surfaces without removing any of its material, and fastening or securing straps 13, 13, having suitable buckles 14, 14, and companion or correlated spaced-apart holes 15, 15, are extended through such slits or openings and are long enough in addition to extend around the collar.

Each such incision or slit through the rubber body and the introduction of the corresponding strap in place therein may be effected with facility by hooking the strap on to the end of a flat metal strip of proper width, thickness and length and with a sharp point at its front end and forcing such metal member through the sponge-rubber and causing the strap to be pulled along with it, so that the strap occupies the slit cut by the metal strip, it being understood that by so doing, practically none of the rubber is removed.

Owing to the fact that no material is taken from the pad during the slitting or cutting operation, and, whereas the straps necessarily have some thickness, the rubber bearing on the straps is slightly compressed thereby holding the straps from becoming accidentally dislodged or displaced before the pad is applied to the collar.

It will, of course, be understood that such pads will wear out in time and that the straps may be readily withdrawn from such an unserviceable pad and applied to a new one, or, viewed somewhat differently, the pads are detachable and easily replaceable.

Due to the effective porosity of the pad throughout its whole thickness including its opposite surfaces, and by reason of its elasticity and resiliency, it will be clear that the attainment of all of the stated objects and purposes of the invention are secured by this simple structure which is comparatively economical to produce.

The invention, as defined by the appended claim, which should be construed as broadly as permitted by the state of the prior art, is not necessarily limited and restricted to the precise and exact details herein set forth, and changes may be resorted to without departure from the heart and essence of the invention and without the loss or sacrifice of any of its material benefits and advantages.

I claim:

A horse-collar pad composed of a sponge-rubber body porous throughout its entire thickness to provide it with ventilating characteristics and slit crosswise, without removal of substantially any of the rubber, and straps occupying said slits for attachment of the rubber body to a horse-collar.

ARTHUR WESLEY.
